(57) **CLAIM**

The ornamental design for a solar cooking apparatus, as shown and described thereof.

DESCRIPTION

FIG. 1 illustrates the front view of the solar cooking apparatus according to the present invention;

FIG. 2 illustrates the back view of the solar cooking apparatus according to the present invention;

FIG. 3 illustrates the left side view of the solar cooking apparatus according to the present invention;

FIG. 4 illustrates the right side view of the solar cooking apparatus according to the present invention;

FIG. 5 illustrates the top view of the solar cooking apparatus according to the present invention;

FIG. 6 illustrates the bottom view of the solar cooking apparatus according to the present invention;

FIG. 7 illustrates the front view of the two open and rotating reflectors of the solar cooking apparatus according to the present invention;

FIG. 8 illustrates the back view of the two open and rotating reflectors of the solar cooking apparatus according to the present invention;

FIG. 9 illustrates the top view of the two open and rotating reflectors of the solar cooking apparatus in open position according to the present invention;

FIG. 10 illustrates the bottom view of the two open and rotating reflectors of the solar cooking apparatus in open position according to the present invention;

FIG. 11 illustrates the right side view of the two open and rotating reflectors of the solar cooking apparatus in open position according to the present invention;

FIG. 12 illustrates the left side view of the two open and rotating reflectors of the solar cooking apparatus in open position according to the present invention;

FIG. 13 illustrates the top perspective view of the solar cooking apparatus with the two rotating reflectors in a closed position according to the present invention; and,

FIG. 14 illustrates the top perspective view of the solar cooking apparatus with the two rotating reflectors in an open position according to the present invention.
